CLAIM

The ornamental design for a combined dual work surface, wall panel and storage unit, as shown and described.

DESCRIPTION

FIG. 1 is a front perspective view of the combined dual work surface, wall panel and storage unit showing my new design;

FIG. 2 is a top plan view thereof;

FIG. 3 is a rear perspective view thereof; and,

FIG. 4 is a bottom plan view thereof.

FIGS. 1, 3 and 4 are shaded to indicate color contrast.
